LATCH

Filed Sept. 3, 1929

INVENTOR.
RAYMOND G. MOORE
BY
Samuel Mather.
ATTORNEY.

UNITED STATES PATENT OFFICE

RAYMOND G. MOORE, OF BRIDGEPORT, CONNECTICUT, ASSIGNOR TO THE BASSICK COMPANY, OF BRIDGEPORT, CONNECTICUT

LATCH

Application filed September 3, 1929. Serial No. 389,921.

The present invention relates to latches, particularly for automobile doors, and has for an object to provide a latch in which the handle shaft is adapted to be secured in such relation to the latch that it cannot be removed by unauthorized persons, when the latch is locked, should such persons succeed in disengaging the escutcheon plate, which is ordinarily the only means for retaining the handle against longitudinal movement. A further object is to provide a construction in which the handle shaft may be inserted into relation with the latch during assembly of the automobile with facility and without the necessity for employing special tools, keys, and the like.

With the above and other objects in view, embodiments of the invention are shown in the accompanying drawing, and these embodiments will be hereinafter more fully described with reference thereto, and the invention will be finally pointed out in the claims.

In the drawing:

Fig. 1 is a plan elevation of an automobile door latch, according to the present embodiment of the invention, the handle shaft being shown in section.

Fig. 2 is a vertical sectional view, taken along the line 2—2 of Fig. 1, and showing the latch in its relation in the door.

Fig. 3 is a side elevation of the handle and shaft employed.

Fig. 4 is an inner end view thereof.

Fig. 5 is a vertical sectional view of the roll-back and a portion of the handle shaft, and showing the manner of engaging the shaft with the roll-back.

Fig. 6 is a plan elevation of a modified form of the invention.

Fig. 7 is a sectional view thereof, taken along the line 7—7 of Fig. 6.

Similar reference characters indicate corresponding parts throughout the several figures of the drawing.

Referring to the drawing, the exemplary latch embodying the present improvements comprises a base plate 10 provided with a flange 11 at its forward end having a latch bolt opening 12 therein. The latch bolt 13 is

slidably engaged at its nose end 14 in the opening 12, and is retained against displacement by means of a cover plate 15 secured to the base plate. A coil spring 16 engaged with the inner end of the bolt normally presses it to its projected position.

At the rearward end of the bolt there is provided an upwardly projecting vertical extension 17 engaged by the inner handle roll-back 18, the hub 19 of which has bearing in apertures formed in the base and cover plates 10 and 15. A coil spring 20 normally engaged at one end with a lug 21 on the roll-back, and engaged at its other end against a lug 22 struck from the base plate yieldably retains the roll-back in its normal position by engaging a projection 23 thereon with the lug 22.

The bolt is adapted to be actuated by the outside handle roll-back 24, through engagement with an upwardly and forwardly projecting arm 25 formed on the bolt.

The outside handle roll-back 24 has its hub portion 26 rotatably engaged at one side in an aperture 27 in the base plate, and at the other side in a circular boss 28 pressed up from the cover plate and spaced from the inner end surface of the roll-back to provide a circular pocket. The roll-back is provided with the usual square or polygonal opening 29, and the boss 28 is provided with a circular opening 30 of a diameter adapted to permit rotation therein of the handle shaft, and provided at diametrically opposed points with radially extending cut-outs 31 and 32.

The handle 33 is provided with the usual escutcheon plate 34 secured thereto, and a key operated lock 35, adapted in the locked position to engage with a locking dog 36 secured in the door to prevent rotation of the handle. A shaft 37, of square cross-section, is secured to the handle and is adapted to fit the square opening 29 of the roll-back. In the usual type of lock it is possible in the locked relation to unscrew the escutcheon plate and then withdraw the handle, whereupon a plane square shaft may be inserted into the roll-back and the latch operated to open the door. The present improvements are intended to prevent such unauthorized

withdrawal of the handle shaft and opening of the door.

Upon the opposed edges of the shaft, and in spaced relation to the end, a pair of lugs 5 or fins 38 and 39 are pinched out in such relation that they may pass through the cut-outs 31 and 32, these lugs being rotatably disposed in the pocket formed by the boss 28 in the assembled relation, as shown in Figs.

10 1 and 2. In the locked relation of the handle shaft the lugs 38 and 39 are beneath the circular flange of the boss, out of register with the cut-outs 31 and 32, and withdrawal of the handle shaft is prevented. As the locking 15 of the handle prevents relative rotary movement of the shaft, rotation of the shaft to turn the lugs 38 and 39 into register with the cut-outs 31 and 32 is impossible, even though the escutcheon is unscrewed.

20 In order to assemble the handle it is only necessary to engage the end of the shaft in the roll-back opening, the circular opening 30 permitting this, as shown in Fig. 5, and then turning the roll-back to a point where 25 the lugs 38 and 39 register with the cut-outs 31 and 32, whereupon the handle shaft is pressed into position with the lugs in the socket of the boss. Upon insertion of the 30 handle the escutcheon is secured in the usual manner to the door front.

As clearly indicated in Fig. 1 the lugs lie beneath the circular flange of the boss in the retracted and locked relation of the roll-back, effectually preventing withdrawal of the handle shaft. The circular flange provides a uniform abutment at all points of rotation of the handle shaft relatively thereto.

In Figs. 6 and 7 I have shown a modified form of the invention, in which the inner 40 end of the roll-back hub has bearing in the usual circular hole 40 of the cover plate. A separate locking plate 41, having a flanged end 42, and provided with the circular opening 30 and diametrically opposed cut-outs 45 31 and 32, is secured to the casing by lugs 43 engaged in suitable slots therein. The operative relation with the handle shaft is the same as in the first embodiment, the lugs 38 and 39 being disposed in the pocket formed 50 beneath the plate.

I have illustrated and described preferred and satisfactory embodiments of the invention, but it will be obvious that changes may be made therein, within the spirit and scope 55 thereof, as defined in the appended claims.

Having thus described my invention, what I claim and desire to secure by Letters Patent is:

1. In a latch, a latch casing, a latch bolt, 60 a roll-back for retracting said bolt having a non-circular opening therein, a handle shaft of non-circular cross-section adapted to be longitudinally engaged with said roll-back opening and including a laterally projecting 65 abutment in spaced relation to the end, abut-

ment means secured to the latch casing having an opening adapted to permit insertion and rotary movement therein of the non-circular roll-back engaging portion of said shaft, said abutment means adapted to abut 70 said laterally projecting abutment upon longitudinal withdrawal movement in the normal non-bolt-retracting position of said roll-back.

2. In a latch, a latch casing, a latch bolt, 75 a roll-back for retracting said bolt having a non-circular opening therein, a handle shaft of non-circular cross-section at its end adapted to be longitudinally engaged with said roll-back opening and including a laterally 80 projecting abutment in spaced relation to the end, abutment means secured to the latch casing having an opening adapted to permit insertion and rotary movement therein of the non-circular end of said shaft and having a cut-out portion adapted to permit passage therethrough of said laterally projecting abutment in a given position of rotation of said shaft, said abutment means adapted to abut 85 said laterally projecting abutment upon longitudinal withdrawal movement in the normal non-bolt-retracting position of said roll-back.

3. In a latch, a latch casing, a latch bolt, a roll-back for retracting said bolt having a non-circular opening therein, and including a hub, a circular apertured abutment boss provided on said casing and adapted to form a bearing for said hub, the inner surface of said boss being spaced from the inner end 110 of said hub to provide an annular pocket, a handle shaft of non-circular cross-section adapted to be longitudinally engaged with said roll-back and including abutment means disposed in said annular pocket, said boss adapted to abut said abutment means upon longitudinal withdrawal movement in the normal non-bolt-retracting position of said roll-back.

4. In combination a latch including a latch casing, a latch bolt, and a roll-back for retracting said bolt, a handle shaft adapted to be engaged with said roll-back and to be turned to rotate said roll-back, locking means associated with said shaft adapted to be actuated to prevent rotation of said shaft, and means cooperating between said latch casing and handle shaft adapted in the locked relation of said handle shaft to prevent longitudinal withdrawal movement thereof, and said means being arranged to provide a circumferential clear space about said handle shaft adapted to permit engagement of said handle shaft with the roll back in any position of rotary adjustment of said handle shaft.

Signed at Bridgeport, in the county of Fairfield, and State of Connecticut, this 29th day of August, 1929.

RAYMOND G. MOORE.
